UNITED STATES PATENT OFFICE.

EDWIN E. STRAW, OF MARSHFIELD, OREGON.

TANK.

941,895.

Specification of Letters Patent. Patented Nov. 30, 1909.

Application filed April 2, 1909. Serial No. 487,412.

To all whom it may concern:

Be it known that I, EDWIN E. STRAW, a citizen of the United States, and a resident of Marshfield, in the county of Coos and State of Oregon, have invented a new and Improved Tank, of which the following is a full, clear, and exact description:

The invention relates to water distribution, and its object is to provide a new and improved tank for flushing water closets, and for filling wash basins, bath tubs and the like, the tank being arranged to discharge a predetermined quantity of water at a time, to insure automatic filling of the tank without danger of overflow or leakage, and to render the operating mechanism noiseless, strong and durable, not liable easily to get out of order.

The invention consists of novel features and parts and combinations of the same, which will be more fully described herein-after and then pointed out in the claims.

A practical embodiment of the invention is represented in the accompanying drawings forming a part of this specification, in which similar characters of reference indicate corresponding parts in both views.

Figure 1 is a sectional side elevation of the improvement arranged as a flushing tank for a water closet and actuated by the seat cover of the water closet; and Fig. 2 is a similar view of the improvement arranged for manual operation.

A closed vessel A, is provided in the center of its inverted cone-shaped bottom A', with a valve seat A², and on one side of the said bottom A' is arranged a depression A³, into which discharges the end B' of the water supply pipe B, connected with a street main or other suitable source of water supp'y.

On the seat A² is adapted to be seated a float valve C, preferably in the form of a hollow metallic ball readily passing to its seat A² when the vessel A is empty, owing to the inclined bottom A', which thus acts as a guideway for the float valve C. The float valve C is normally held to its seat A² when the vessel A is filled with water, by the pressure of the water, and the float valve C is capable of rising in the water after being dislodged from its seat A² in the manner hereinafter more fully described.

On the under side of the bottom A' and extending diametrically across the valve seat A² is arranged a cylindrical valve casing D, connected at its bottom wi' an out-

let pipe E, leading to the water closet bowl F, or other receptacle to be flushed or filled with a quantity of water contained in the vessel A. In the casing D is mounted to slide laterally a correspondingly-shaped valve G, having its valve stem G' extending through a stuffing box D' in one end of the casing D, the outer end of the valve stem G' being either connected by a link H with the hinged end of the water closet seat I, or the said valve stem G' is provided with a knob G² (see Fig. 2) under the control of an operator.

By reference to the drawings, it will be seen that the valve seat A² intersects the top of the valve casing D, so that when the valve G is in an open or withdrawn position and the float valve C is on the seat A², then the bottom of the said float valve C extends into the valve casing D.

The forward end G³ of the valve G is made tapering, to readily engage the projecting lower end of the float valve C whenever the valve G is pushed inward in the direction of the arrow a', either by the operator lifting the seat cover I or pushing the knob G², it being understood that during the inward movement of the valve G the valve C is lifted and thus dislodged from the seat A², to freely rise in the body of water contained in the vessel A. It will also be noticed that when the valve G is moved in the direction of the arrow a', as described, the valve closes the under side of the seat A², thus preventing the escape of the water from the vessel A for the time being, that is, until the valve G is returned to its original position, either by closing the cover I or by the operator pulling on the knob G². Now when this takes place, the seat A² is opened and also the connection between the valve casing D and the pipe E, so that the water from the vessel A now flows into the water closet bowl F, basin, bath tub or other device to be flushed or filled. When the water runs out of the vessel A the float valve C falls with the water in the vessel A, and when the vessel is empty the float valve C is guided back to its seat A² to then close the vessel A at its bottom, and the vessel A now again fills with water supplied by the water supply pipe B.

The top of the vessel A is provided with an air vent J, adapted to be closed at its bottom by a ball valve K, having its stem K' extending up through the vent J, the stem being provided at its top with a cross arm

K², adapted to be seated on the top of the vent J to hold the valve K in an open position, as shown in Fig. 2. When the water rises in the vessel A, it finally moves the 5 valve K to its seat to close the air vent J, as shown in Fig. 1, and when the water flows out of the vessel A the valve K drops to open the air vent J and allow air to pass into the vessel A for the proper discharge of the 10 water from the vessel A, as above explained.

The device shown and described is very simple and durable in construction, is absolutely noiseless and effectively controls the discharge of the water from the vessel A.

15 Having thus described my invention, I claim as new and desire to secure by Letters Patent:

1. A flushing or filling tank, comprising a closed receptacle connected with a water supply and provided in its bottom with a valve seat, a float valve within the said vessel and adapted to seat itself on the said valve seat at the time the vessel is empty, a valve casing underneath the said valve seat and intersecting the same to allow the said float valve to extend into the valve casing, and a shiftable valve mounted to slide in the said valve casing and having a tapering end adapted to engage the said float valve and lift it off its 20 seat.

2. A flushing or filling tank, comprising a

closed receptacle connected with a water supply and provided in its bottom with a valve seat, a float valve within the said vessel and adapted to seat itself on the said valve seat 35 at the time the vessel is empty, a valve casing underneath the said valve seat and intersecting the same to allow the said float valve to extend into the valve casing, a shiftable valve mounted to slide in the said valve casing and having a tapering end adapted to engage the said float valve and lift it off its seat, and a connection between the said shiftable valve and the cover for a water closet, to actuate the said shiftable valve on opening and closing the said cover.

3. A flushing or filling tank comprising a closed receptacle connected with a water supply and provided in its bottom with a valve seat, a float valve within the vessel and co-operating with the seat, a transversely movable valve beneath the seat and adapted to close the opening through the valve seat, said valve having a tapering end for engaging and unseating the float valve.

In testimony whereof I have signed my name to this specification in the presence of two subscribing witnesses.

EDWIN E. STRAW.
